FRANÇOIS LECLÈRE, OF WATERTOWN, NEW YORK, ASSIGNOR TO MOSES EAMES, OF SAME PLACE.

Letters Patent No. 99,327, dated February 1, 1870.

IMPROVEMENT IN BLIND-SLAT MACHINE.

The Schedule referred to in these Letters Patent and making part of the same.

To all whom it may concern:

Be it known that I, FRANÇOIS LECLÈRE, of Watertown, in the county of Jefferson, and State of New York, have invented a new and improved Machine for Tenoning and Pricking Blind-Slats; and I do hereby declare that the following is a full, clear, and exact description thereof, reference being had to the accompanying drawings, making a part of this specification, in which—

Figure 1, sheet 1, is a top or plan view of the improved machine, with a portion of the feed-table broken away.

Figure 2, sheet 2, is a longitudinal central section, taken through the machine, in the vertical plane indicated by red line *x* *x* in fig. 1.

Figure 3, sheet 3, is an enlarged sectional view of the slat-holding, rotating, and discharging-devices of one side of the machine, as seen by making a vertical section, as indicated by the course of the red line *y* *y* in fig. 1.

Figure 4, sheet 3, is an enlarged sectional view of one of the feeding-slides.

Figure 5, sheet 3, is an enlarged sectional view of the tenon-saw and its shaft, of one side of the machine.

Similar letters of reference indicate corresponding parts in the several figures.

This invention relates to certain novel improvements on machinery which is designed for cutting tenons on the ends of window-blind slats, and also, for pricking the edges of the slats, for the insertion of staples.

The nature of my invention consists, chiefly, in the application, to intermittent rotating spur-wheels, which are arranged in parallel planes, at proper distances apart, and whose axes of motion coincide, of devices which will, at proper times, firmly grip and centre the slats, and hold them, one at a time, in position for having tenons formed on their ends, by means of tubular saws, after which the slats will be carried over and presented to two rotating circular saws, when said clamping-devices will be caused to give the slats one revolution, and thus produce the shoulders upon them, as will be hereinafter described.

The invention also consists in combining, with intermittent rotating spur-wheels, which are adapted for carrying slat-clamping and centring devices, certain means which will discharge the slats from their clamps, after being tenoned and shouldered, during the movement of the clamps to a position for receiving other slats, as will be hereinafter described.

The invention also consists in providing for automatically arresting and locking fast the spur-wheels which carry the slat-holding and clamping devices, at proper times for allowing shoulders to be sawed upon the slats, and at the same time releasing and rotating

the clamping-devices, so as to give the slats one revolution while they are being acted upon by the saws, as will be hereinafter described.

The invention further consists in the employment of pricking-spurs upon a reciprocating slide, which is operated in conjunction with feeding-slides, so that after each slat has been forced between its clamps and properly centred, said spurs will advance and prick the slat exactly in the middle of its length, or at any other desired point, for the insertion of the wire staple, and then recede and allow the slat to be tenoned and shouldered, as will be hereinafter described.

The invention further provides for adapting the machine for pricking, tenoning, and shouldering slats of different lengths and widths, as will be hereinafter described.

The invention further provides for the use of adjustable spring-guides and feeding-devices, for facilitating the introduction of slats to the clamps, and properly adjusting the slats between said clamps, so that no great care or experience will be required to keep the machine supplied with work.

To enable others skilled in the art to understand my invention, I will describe its construction and operation.

In the accompanying drawings—

A represents a rectangular frame or table, which is adapted for containing and steadily supporting the several parts of the machine.

*A*¹ *A*¹ represent two horizontal transverse beams, which are secured firmly on top of and near the extremities of the frame *A*, which beams have tenons formed on their upper surfaces, that receive corresponding grooves, formed in two longitudinal frames, *A*² *A*², and allow the latter to be moved in a lateral direction, and secured at any required distance apart, according to the length of the slats to be subjected to the machine.

These two laterally-adjustable frames *A*² *A*² are rigidly secured, by bolts or clamps, to frame-beams *A*¹ *A*¹, after they are adjusted, so that they afford firm bearings for the several parts which they are designed to support.

At the front end of the machine, and supported upon perpendicular standards *a* *a*, is a table, *A*³, which is hinged to said standards and inclined forward, so as to rest, at its front end, upon the frames *A*² *A*², as shown in fig. 2.

Upon this table are two guides, *a*¹ *a*¹, which converge toward the rear end of the machine, and terminate at their front ends in inclined plates, which extend down below the table *A*³, so as to deliver the slat-blanks upon the horizontal ways *A*⁴ *A*⁴ *B*, in front of the sliding feeders, and between two spring-guides *B*¹ *B*², shown in fig. 1.

The table-guides are secured upon their table *A*³,

by means of clamp-screws, passing through transverse slots, made through the table, so that these guides can be adjusted and set for slats of different lengths.

The springs $B^1 B^2$ are secured to the inner sides of their respective frames $A^2 A^2$, and their forward ends project some distance beyond the forward edge of table A^3 , and bend inward, or toward the centre of the machine, so as to press gently upon the ends of a slat which is being moved between them, and thus bring such slat in a proper position, with respect to the devices for clamping it, as will be hereinafter more fully explained.

A set-screw, a^2 , fig. 1, is employed for adjusting the spring-guide B^2 , and obtaining a very nice adjustment of the slat, with respect to the tenon-saws and shoulder-saws.

The longitudinal ways B are arranged exactly in the middle of the width of the machine, and firmly secured to the frame A beneath table A^3 .

Between these ways a slide, B^3 , moves, to which is secured a longitudinally-adjustable plate, b , having a spurred plate, b^1 , secured to its forward end, as shown in figs. 1 and 2. These spurs are held in a proper position to move up and prick the slat, when it has been forced home between its clamps.

The slats are usually pricked in one of their edges, and about the middle of their length, as indicated by the position of the parts in figs. 1 and 2.

The ways $A^4 A^4$ are arranged parallel to and equidistant from the way B , and in the same horizontal plane therewith.

Slides $C C$, having lugs projecting up from them, are applied, for the purpose of carrying the feeding-heads $b^2 b^2$, which move the slats, one at a time, between their clamps.

These heads b^2 are applied on the front ends of screw-rods b^3 , which pass loosely through the lugs on slides $C C$, and receive adjusting-nuts b^4 on their rear ends, as shown in figs. 1 and 4.

On each screw-rod, b^3 , a collar is fixed, between which and the rear lug of the slide C , a spring, b^5 , is applied, which presses the head b^2 forward, and holds it in position to move forward a slat put upon the ways.

The three slides A^4 , A^4 , and B , are connected to a horizontal transverse bar, C^1 , the extremities of which project beyond the outer sides of the frames $A^2 A^2$, and receive adjustable collars upon them, and also the ends of connecting-rods $C^2 C^2$. These rods C^2 proceed toward the rear end of the machine, and are connected to cranks $C^3 C^3$, upon the horizontal rotary shafts $D D$, shown in fig. 1.

As the shafts $D D$ rotate, the three slides and their attachments receive an alternate reciprocating motion.

In front of the ways $A^4 A^4$ are two large spur-wheels, $E E$, of an equal diameter, which are keyed on the inner ends of shafts $E^1 E^1$, whose axes coincide.

The shafts of spur-wheels $E E$ have their bearings in journal-boxes upon the frames $A^2 A^2$, and receive an intermittent rotary motion from the segment spur-wheels $F F$, upon crank-shafts $D D$, which latter also have their bearings on frames $A^2 A^2$.

The two wheels $E E$ are constructed alike in every particular, for which reason it will not be necessary to refer to both in describing their construction.

I make circular openings through the wheel E , diametrically opposite each other, of such diameter as to receive the flanged circular holders $C C$, so that the latter will rotate freely. These holders $C C$ have openings made through them, extending from their peripheries to and beyond their centres, which openings are of sufficient size to allow of the introduction and centring of the slats, as shown in fig. 2. Corresponding with these openings through the circular slat-holders $C C$, I make openings through the circumference of the wheel E , which allow the slats to be introduced edgewise into these holders C , when the latter are locked in the position shown in fig. 3.

The inner flanges of said holders C are toothed, as shown at C^1 , for the purpose of engaging with the teeth of a segment, C^2 , which is secured on one side of the wheel F , in the same vertical plane as the teeth C^1 , and allowing said segment to give one of the slat-holders a revolution about its axis at every half revolution of the wheel E , as will be hereinafter further explained.

On the outer surfaces of the slat-holders $C C$, I pivot clamping-jaws g^1 , which are pressed together by means of springs, g^2 . These jaws are pivoted at opposite ends, and properly adjusted by means of set-screws g^3 , passing through the free end of one jaw, and pressing upon the pivoted end of its opposite jaw, as shown clearly in fig. 3. Those ends of the jaws of both holders $C C$, which are nearest the circumference of wheel E , are bevelled, so as to flare outward, so as to be forced open when a slat is pressed edgewise between them; and those portions of the jaws which embrace the slats, are shaped so as to conform to the shape of these slats in cross-section. When these jaws are properly adjusted for a slat of a given size, thickness, and width, by the set-screws g^3 , they will snugly hold the slats in a central position with respect to the holders C , so that these slats will be properly presented to the work of tenoning and shouldering.

On the inner side of each one of the slat-holders c , is a gauge, g^4 , consisting of a right-angular plate, slotted, and confined in place by means of adjusting-screw h and binding-screw h^1 .

That portion of the gauge g^4 which is at right angles to the length of the opening through the slat-holder, forms an abutment or stop, against which the slats are pressed by the feeding-heads $b^2 b^2$, and held by the clamping-jaws $g^1 g^1$.

Notches are made in the peripheries of the flanges, on the outer sides of the slat-holders c , for the reception of dogs $h^2 h^2$, which latter are pressed against said flanges by means of springs $h^3 h^3$, shown in fig. 3, and at suitable times, are thrown back and released from their notches, by the action of a wedge, h^4 , upon studs, h^5 , projecting from said dogs.

The wedge h^4 is upon a vibrating bent arm, F^4 , which is acted upon by a cam on the shaft D of wheel F .

The two slat-holders $c c$, on one wheel, E , are arranged so that their axes coincide with the axes of the corresponding holders on the opposite wheel E ; therefore, when a slat is confined between the clamping-devices of each pair of holders, such slat will be in a horizontal plane parallel to the axes of the two wheels $E E$.

The wheels $E E$ receive motion from the spurs, which are made upon one-half of the two spur-wheels $F F$, which spurs are in planes with their respective wheels $F F$. These latter wheels receive an intermittent revolution about their axes; that is to say, the two wheels $E E$ are caused to make one-half of a revolution, so as to bring the two slat-holders on one side of the wheels $E E$, into gear with the segments $c^2 c^2$ on wheels $F F$, and the two slat-holders $c c$, on the opposite side of the axes of wheels E , in position for receiving a slat from the ways $A^4 A^4$. When in these positions, the two slat-holders nearest the wheels F , will receive a complete revolution about their axes by the action of segments c^2 upon them, after which the wheels E will again receive a half revolution, and the other two slat-holders will be brought into gear with segments c^2 , and rotated.

During the operation of feeding a slat into the slat-holders, and sawing the shoulders upon another slat, the two wheels $E E$ will be firmly held, and prevented from turning, by the interlocking of teeth $i i$, into notched plates $i^1 i^1$ upon the said wheels. These locking-teeth $i i$ are upon the extremities of overhanging spring-arms, $G G$, which are secured to the rear ends of frames $A^2 A^2$, and which are acted upon by cams $j j$, upon the shafts $D D$, so as to be lifted at the mo-

ment the segments c^2 leave the teeth of the slat-holders, and the teeth on wheels F commence to rotate the wheels E.

Two horizontal transverse saw-arbors, G' G', have their bearings upon the frames A², and are arranged so that their axes exactly coincide with the axes of motion of the slat-holders, when the latter are brought to a position for receiving a slat, as clearly shown in fig. 1. These two saw-arbors, G', are allowed to receive a rapid rotary motion, and, at the same time, end play.

The rotary motion is given to said arbors by means of a belt leading from a long drum, Z, and the end-wise movements are imparted to them by means of vibrating levers H, which are acted upon by cams H' on shafts D, for pressing the arbors inward at every half revolution of the wheels E, and also by means of helical springs k k, arranged below the arbors, and acting upon them, to press them outward, by means of rods k' and the yoke-plates k², which latter embrace annular grooves made in the outer extremities of said arbors.

The small set-screws k³, which pass through the front ends of levers H, and abut against the plates k², admit of there being a greater or lesser throw given to the arbors G'.

Upon the inner ends of the saw-arbors, I affix, centrally, tubular saws l l, the object of which is to cut into the ends of slats, confined in the slat-holders c c, and produce tenons on said slats, leaving the wood, surrounding the tenons, to be cut away by two circular saws, I I, applied on the ends of arbors I' I'.

The saws I I are arranged in planes at right angles to the slats confined upon the wheels E E, and the arbors of said saws are supported in journal-boxes I' I', which are longitudinally adjustable upon the frames A² A². The journal-boxes I' are made adjustable, in order to compensate for the wearing and sharpening of the saws.

The two spurred wheels F F are rotated constantly in one direction, during the operation of the machine, by means of two pinion-spur wheels J J, which are of sufficient length to engage with the teeth formed on the side segments c², the teeth formed on the intermediate segments c², and also with the teeth which are formed directly upon the circumference of said wheels.

These pinions are applied upon a horizontal transverse shaft, J¹, extending across the rear part of the machine, and having its bearings in standards J² J², projecting up from the sides of frame A. The shaft J¹ is grooved throughout its length, and the pinions J J are secured to it by means of keys or tenons formed on them, so as to allow them to be adjusted endwise, for adapting the machine for slats of different lengths.

The pinions J J are kept in place on their shaft by the brackets J³ J³, which are secured to the laterally-adjustable frames A² A², and constructed with eye-bearings at both ends of each pinion.

Upon the lower sides of both frames A² A², brackets K (one of which is shown in fig. 2) are applied, through the lower ends of which a horizontal screw-shaft, L, passes, which shaft extends transversely across frame A, and is supported in hangers projecting down from the top rails thereof. This shaft L has right and left-hand screw-threads formed upon it, working in corresponding threads formed in the brackets K. When the clamps or screw-rods are removed from the frames A² A², they can be readily adjusted, and set at any required distance apart, by simply turning the screw L toward the right or left hand.

The tenoning-saws l l and the shouldering-saws, receive their motion from the horizontal transverse drum Z, by means of belts passing around pulleys on the arbors of said saws. The shaft J¹ receives rotation from the main driving-shaft, through the medium of

pulleys and belts, which also communicate motion to the drum Z.

Operation.

The slat-blanks, which have all been cut of an equal length, are laid upon the table A³, and moved forward between the table-guides a, upon the guards F, or allowed to drop, one at a time, in front of the feeding-head or plungers b², when the latter have completed their backward stroke.

These slats drop upon the ways A⁴ A⁴, B, and between the spring-guides B¹ B².

When the heads b² b² move forward, they carry with them a slat, and force it in its place between the clamps g g', of the slat-holders c c, farthest from the saws I.

When a slat has been forced between its clamps by heads b², and brought against the stops g⁵, the springs b⁵ yield, and allow the slide B³ to complete its forward stroke, in doing which, the spurs on plate b¹ perforate the edge of the slat, for receiving a wire staple.

During the pricking of the slat-eams, H' H' act upon the tubular saw-arbors G', through the medium of levers H, and move the saws l l up the required distance to saw cylindrical tenons upon the ends of said slat, after which the saws l l recede, and the three slides, C, C, and B³, commence their backward stroke.

As soon as the slat is released from its tenon-saws and pricking-spurs, the teeth i i are thrown up by cams j j acting upon spring-arms G, and the two spurred wheels released. These wheels then move in the direction indicated by the arrow in fig. 2, until they are again caught and held by the spring-teeth i i, when the segments c², on wheels F F, will be brought into play, and rotate the slat-holders c c, nearest them, during which operation the two saws I I will produce the square shoulders upon the ends of the slat, thereby exposing the tenons previously cut by the tubular saws l l.

During the operation of sawing the shoulders upon one slat, another slat-blank is being forced into its holding-devices on the opposite side of the axes of the wheels E, and tenoned, so that when the shouldering-saws complete their work, and the wheels E start again, there will be another slat ready to be shouldered.

As the wheels E revolve, and the slats are brought to a position to be shouldered, the wedges h⁴ on levers F⁴ will press back the dogs h², and release the slat-holders, so that they may be rotated. When said slat-holders have made one complete revolution, the dogs h² will spring back into their notches, and lock said holders until they come around again.

When the slat-holders make one revolution, and are locked fast by their respective spring-dogs, wheels E E are then moved by wheels F F, so as to carry the finished slat beneath the table and beneath two eccentric flanges M M, which are secured to the inner sides of frames A². These flanges are eccentric to the axes of the wheels E, and press upon the slat, so as to force it from between its clamps, and finally discharge it from the said wheels.

It will be seen from the above description, taken in connection with the accompanying drawings, that the devices for tenoning and shouldering one end of a slat, are upon one frame, A², and the devices for similarly treating the other end of the slat, are on the other frame, A²; consequently, slats of different lengths can be tenoned and shouldered by properly adjusting said frames.

Having described my invention,

What I claim as new, and desire to secure by Letters Patent, is—

1. The yielding feeding-heads b² b², in combination with a device for pricking slats, substantially as described.

2. The converging spring-guides B^1 B^2 , for guiding the slats properly to their work, substantially as described.
3. Supporting the slats, during the operation of tubular tenoning-saws upon them, by means of slat-holders c c , applied to intermittent rotating wheels E E , substantially as described.
4. The adjustable stop-gauges g^5 , applied to the slat-holders c , substantially as described.
5. The spurred wheels E E , adapted for receiving and holding slats, and presenting them to tenoning, shouldering, and discharging-devices, substantially as described.
6. The cams or tripping-wedges h^4 , and dogs h^2 , in combination with rotary slat-holders c , applied and operating substantially as described.

7. The combination of shouldering-saws I , with devices applied to wheels E , for holding and rotating the slats, when presented to said saws, substantially as described.

8. The stops i i , in combination with wheels E , carrying slat-holding devices, substantially as and for the purposes described.

9. Communicating an intermittent rotary motion to wheels E , carrying slat-holding devices, by means of the segment spur-wheels, F , which also rotate the said slat-holders, substantially as described.

FRANÇOIS LECLÈRE.
